(57) **CLAIM**

The ornamental design for a surface configuration of a door for a vehicle, as shown and described.

DESCRIPTION

FIG. 1 is a front view of a first embodiment of a surface configuration of a door for a vehicle according to my novel design;

FIG. 2 is a perspective view of the first embodiment of the surface configuration of a door for vehicle according to my novel design;

FIG. 3 is a front view of a second embodiment of the surface configuration of a door for a vehicle according to my novel design; and,

FIG. 4 is a perspective view of the second embodiment of the surface configuration of a door for a vehicle according to my novel design.

The broken lines included in the drawings depict environment and are not part of the claimed design.

This application is related to the following co-pending applications, of the inventor, filed on even date herewith:

Application Ser. No. 29/151,801, entitled “surface configuration of a Vehicle and Toy”;

Application Ser. No. 29/151,817, entitled “Surface Configuration of a Door for a Vehicle”; and,

Application Ser. No. 29/151,814, entitled “Surface Configuration of a Side of a Vehicle”.
